UNITED STATES PATENT OFFICE.

RUDOLF EICKEMEYER, OF YONKERS, NEW YORK.

DYNAMO-ELECTRIC GENERATOR.

SPECIFICATION forming part of Letters Patent No. 369,400, dated September 6, 1887.

Application filed February 9, 1887. Serial No. 227,020. (No model.)

To all whom it may concern:

Be it known that I, RUDOLF EICKEMEYER, of Yonkers, in the county of Westchester and State of New York, have invented certain 5 new and useful Improvements in Dynamo-Electric Machines or Electric Generators; and I do hereby declare that the following specification, taken in connection with the drawings furnished and forming a part of the same, is a 10 clear, true, and complete description of my invention.

In my application for Letters Patent, filed March 2, 1885, Serial No. 157,545, I disclosed certain improvements in machines of the bi-polar variety, and therein two general types of machines were illustrated, in one of which the exciting-helix was inclosed by a magnetic shell and surrounded the armature diametrically, and certain specific claims were therein 15 based thereon. In the other of said types the armature was surrounded concentrically by the exciting-helix, and both were inclosed by a magnetic shell, and, while this form of machine was embraced in general terms within the meaning of certain of my claims in said application, I was precluded therein from making specific claims to this particular type of machine, and hence this application.

I should also here state that in my Letters Patent No. 342,504, issued on my application filed November 8, 1882, Serial No. 76,234, I disclosed certain forms of unipolar machines which embodied an armature, an exciting-helix concentric with the armature, and a magnetic shell which concentrically inclosed them; and, also, that in my Letters Patent No. 351,906, dated November 2, 1886, I disclosed certain forms of multipolar machines, which also embodied an armature, an exciting-helix concentric with the armature, and a magnetic shell which concentrically inclosed the helix and armature, thus clearly indicating that the features which I now seek to specifically cover by Letters Patent are not only restricted to bi-polar machines, but also to those forms of my machines in which the armature is surrounded concentrically by the exciting-helix and both are concentrically inclosed by a magnetic shell.

50 Referring to the two sheets of drawings, Figure 1 is a side elevation of a cylindrical-armature machine embodying my said improvements.

Fig. 2 is an end view of the same without the driving-pulley. Fig. 3 is a partial top or plan view of the same, but with the exciting-helix and magnetic shell shown in section. Fig. 4 is an end view of the magnetic shell of the machine with all the interior parts removed. Fig. 5 is a side elevation of a shell or casing for a disk-armature machine. Fig. 6 is a horizontal central section of a disk-armature machine having a magnetic shell, as in Fig. 5.

In the machine shown in Figs. 1 to 4, inclusive, the cylindrical shell or casing A is composed of iron and constructed in two or more parts bolted together, and it has a base, a, by which it can be properly mounted on a suitable foundation, and, also, the brackets b for supporting the shaft of the cylindrical armature B. The interior of the shell is annularly recessed for the snug reception of the exciting-helix C, having an interior diameter slightly greater than the armature.

The shell is cut away at each end at diagonally-opposite points for reducing the weight 75 of the shell and developing the diagonally-opposite semi-cylindrical or concave cheeks or pole-faces c c'. The brackets b are bolted to the outer sides or ends of the cheeks, and each has a bearing for the shaft d of the armature, and one of said brackets also supports the commutator-brushes D. Power is applied to the opposite end of the shaft at the belt-pulley e.

The armature B here shown is of a usual 85 form, cylindrical, and having one or more electric conductors, g, terminating at the hub g'. These conductors are wound longitudinally upon a core of magnetic metal, which constitutes a part of the electro-magnet in the machine, it being directly polarized by the exciting-helix, which also develops poles at the cheeks c c', each being opposite in polarity to the pole developed at the adjacent end of the armature-core, and the cylindrical portion of 90 the shell completes the magnetic circuit. In operation, with the helix duly excited, a magnetic circuit is induced, which includes the core longitudinally, and passes from one end thereof to the adjacent cheek-piece and thence 95 through the cylindrical portion of the shell to the opposite cheek, and thence to the armature-core, thus completing the circuit, which is cut between the cheeks and the core by the

armature-conductors in a manner well known.

In Fig. 6 the armature B' is of a well-known type, in disk form, its conductor g terminating at the commutator-hub g' in the usual manner. The magnetic shell A', Figs. 5 and 6, differs from the shell previously described, in that it is specially formed to co-operate with the disk-armature and has diagonally-opposite flat cheeks or pole-faces $h h'$. The helix C', as before described, is concentric with the armature and directly polarizes the iron therein, and the magnetic shell surrounds the exciting-helix concentrically, thus, as in the other form described, developing opposite polarity in the cheeks and also developing appropriate poles in the armature, and the magnetic circuit includes the armature-core diametrically, the two cheeks, and the cylindrical portion of the shell.

I have not deemed it necessary to illustrate the terminals of the exciting-helices, nor the conductors by which they may be coupled to an electric supply, such matters being readily understood and quite immaterial for the purposes of this specification.

Having thus described my invention, I claim as new and desire to secure by Letters Patent—

1. In a bipolar dynamo-electric machine or electric generator, the combination of an armature, an exciting-helix concentrically surrounding said armature, and a shell of magnetic metal which concentrically surrounds said helix and is polarized by it for developing pole-faces at diagonally-opposite points at the interior of the shell. 30

2. In a bipolar dynamo-electric machine or electric generator, the combination of an armature embodying magnetic metal, an exciting-helix concentrically surrounding and directly polarizing said armature, and a shell composed of magnetic metal which concentrically surrounds said helix is polarized by it, and has interior diagonally-opposite pole-faces. 35

RUDOLF EICKEMEYER.
